UNITED STATES PATENT OFFICE.

WILLIAM F. BUBLITZ, OF ELKHORN, WISCONSIN.

CRAMPING FORM FOR VIOLIN BOUTS.

1,415,144.

Specification of Letters Patent. Patented May 9, 1922.

Application filed July 9, 1921. Serial No. 433,585.

To all whom it may concern:

Be it known that I, WILLIAM F. BUBLITZ, a violin maker, citizen of the United States, residing at Elkhorn, in the county of Walworth and State of Wisconsin, have invented 5 certain new and useful Improvements in Cramping Forms for Violin Bouts, of which the following is a specification, reference being had to the accompanying drawings.

10 This invention relates to what are known in the art as cramping forms, and more particularly to cramping forms used in the construction of violin bouts.

In the manufacture of violins, the bouts 15 or sides, before being secured to the back and belly of the instrument are first formed into proper shape of three pieces of material which are glued together and subsequently have their reinforcing strips attached to 20 their marginal edges. In forming these strips, they are preferably ironed into their approximate shape and then cramped into position in the gluing form and after becoming set are removed, trimmed up and 25 made ready for the subsequent attachment of the belly and back.

In previous forms the removal of the bouts from the form was made extremely difficult owing to the fact that the excessive 30 glue which oozed out of the joint between the center of the bout and the forward or rear bouts, sometimes called the end bouts, adhered to the mold with such tenacity as to require insertion of a knife between the 35 bouts and the mold which frequently caused breaking of the bouts and often resulted in bad joints which had to be covered up by purfling. This was resorted to in many instances by the old masters. Another serious 40 defect in the old types of molds was that the bouts stuck to the base of the mold which necessitated the insertion of a knife beneath the bouts and between the same and the base to remove them from the mold.

45 It is the object of this invention, therefore, to avoid such difficulties and to insure a perfect joint being made between the center and end bouts so that the use of purfling to cover up defects may be eliminated, and it is of course also the object of 50 the invention to provide a mold into which the bouts may be readily and efficiently cramped and removed when set without the use of any instrument.

55 Further objects of the invention will appear as the following specific description is

read in connection with the accompanying drawings which form a part of this application and in which:

Figure 1 is a top plan view; 60

Figure 2 is a side elevation;

Figure 3 a transverse section taken on the line 3—3 of Figure 1;

Figure 4 is a detail section taken on the line 4—4 of Figure 1; 65

Figure 5 is a section taken on the line 5—5 of Figure 1.

Referring more particularly to the drawings, 1 represents a base of wood or any other suitable material which has secured 70 to the upper surface thereof a zink plate 2, the purpose of which will be hereinafter described.

Secured upon the top of the plate 2 by bolts or lagscrews 3, which enter the base 1, 75 is the mold form 4 curved at 5, 6 and 7 to receive the upper, intermediate or center, and lower or tail bout of the violin. The curves 5 and 7 are both compound as shown, and the curve for the center bout is substantially one-half of an oval divided upon 80 its longitudinal axis. The curves 5 and 6 and 6 and 7 substantially merge into each other at 8 and 9 to receive the ends of the bouts, and are slightly separated so as to 85 allow a passage 10 to receive the ends of the bouts. These passages communicate with enlarged openings 11 formed in the mold body 4 which are provided to receive and permit removal of any excess glue which is 90 squeezed out from between the joining ends of the end bouts and the center bout.

Any excess glue which may rise to the upper edges of the joined ends can be readily scraped or washed away before it sets and 95 any excessive glue which escapes at the lower edges of the joined ends can be washed or scraped away after removal, it being understood that this excessive glue does not adhere to the zink.

Secured to the base 2 at suitable intervals, 100 are blocks 12 having threaded openings therein to receive the cramping screws 13 which carry upon their outer ends the bout engaging heads 14. Each of these screws is 105 provided with a handle 15 for forcing the heads into engagement with the bouts in a manner which is well known. Each block 12 is preferably provided with an oil hole 16 by which the screw may be properly lubricated.

110 As shown, the inner end of each screw is reduced, at 17, and provided with an annu-

lar groove 18 into which the pin 19, passing through the head, is fitted. This permits of ready rotation of the screw in the head and at the same time prevents its accidental removal from the end of the screw.

In the operation of the device, after the bouts have been ironed to their approximate shape, the center bout has its ends dipped in glue and placed in position around the 10 curve 6. The end or front and tail bouts are then placed in position in the curves 5 and 7, and the screws 15 operated to carry the heads into engagement with the bouts. The center screw is preferably operated first to 15 clamp the center bout tightly against the mold 6, and the corner blocks 20, after being properly coated with glue, are placed in the corners between the end bouts and the center bout as shown. The two outer screws 20 are then operated to bring their heads into engagement with the corner blocks, thus forcing the corner blocks into the corner and the ends of the end bouts and center bout into the passages 10. In this position the bouts 25 conform to the curvature of the mold. The surplus glue is then washed off the top edges of the bouts and at the corners, the openings 11 making the latter operation possible. The bouts are then allowed to remain cramped 30 in the mold until the glue is fully set and then removed and the surplus glue at the bottom edges of the corners is washed or

scraped away. The sides are then ready for the attachment of the belly and back.

What I claim is:

1. In a gluing form for violin bouts, a base, a form secured to the base and having channels for the reception of the ends of the bouts to be joined, the mold being further provided with enlarged openings communicating with the channels, a plurality of upright supporting blocks located on the base, screws threaded through the blocks and provided at one end with handles, and heads swiveled upon the other ends of the screws 40 for cramping the ends of the bouts into the channels.

2. In a gluing form for violin bouts, a base, a form secured to the base and having channels for the reception of the ends of the bouts to be joined, the mold being further provided with enlarged openings communicating with the channels, a plurality of upright supporting blocks located on the base, screws threaded through the blocks and provided at one end with handles, and heads swiveled upon the other ends of the screws 50 for cramping the ends of the bouts into the channels, the axes of the screws all converging to a point beyond the base.

In testimony whereof I hereunto affix my signature.

WILLIAM F. BUBLITZ.
